United States Patent Office.

JAMES NUTTALL, OF WALMERSLY, ENGLAND, ASSIGNEE TO THOMAS ISHERWOOD AND CHARLES MAXSON, OF WESTERLY, RHODE ISLAND.

Letters Patent No. 100,794, dated March 15, 1870; antedated March 4, 1870.

IMPROVEMENT IN TAPPET-CHAIN FOR LOOM.

The Schedule referred to in these Letters Patent and making part of the same

To all whom it may concern:

Be it known that I, JAMES NUTTALL, of Walmersly, in the county of Lancaster, in England, have invented a new and useful Improvement in Looms; and I do hereby declare that the following is a full, clear, and exact description thereof, which will enable others skilled in the art to make and use the same, reference being had to the accompanying drawings forming part of this specification.

This invention relates to improvements in looms, and consists in an improved construction of pattern- or tappet chain for actuating the harness-levers or treadles.

Figure 1 represents a front elevation of a pattern-chain, constructed according to my improvement, as applied to the harness-levers.

Figure 2 represents a section of the same, taken on the line x x of fig. 1.

Figure 3 represents a plan view of one of the tappet-links; and

Figure 4 represents a similar view of one of the ordinary links.

Similar letters of reference indicate corresponding parts.

The rods a for supporting and actuating the tappet links b , are connected at each end by the ordinary curved links c , arranged in the usual manner.

b represents the tappet-links, which are heart-shaped, and provided with two holes, similar to those of the links c for connecting to two rods. These tappets are recessed in their sides, as represented at e , to

permit them to overlap each other when the figure of the goods to be produced requires two or more of the tappets to follow in succession.

This arrangement permits the chain to be changed to produce various patterns, which changes may be accomplished by slipping both the links c and b off the rods and re-arranging them.

I contemplate using two of these pattern-chains, one on each side of the axis of the harness-levers f , under the latter, as represented in fig. 2.

For operating the chains I employ shafts g , fluted throughout their length, the projecting ribs of the said shafts taking into the curves in the base of the tappet-links, similarly to their action with the links c , whereby the tappet-links are more permanently supported to act on the levers, and a more reliable movement of the chains is secured.

The blank spaces on the shafts may be filled with rings h .

Having thus described my invention,

I claim as new, and desire to secure by Letters Patent—

The links b , cut away at their sides, to permit them to overlap each other when the figure of the goods requires, in combination with rods a , links c , and fluted rollers g , as described.

JAMES NUTTALL.
